SUPPORTING AND CLAMPING DEVICE
Willie E. Newton, 134 Pleasant Drive NW,
Albuquerque, N. Mex.
Filed Jan. 8, 1964, Ser. No. 336,601
1 Claim. (Cl. 249—46)

The present invention relates to a device for supporting and maintaining the relative positions and spacing of parallel members, such as concrete forms. More particularly, the present invention relates to an improved device for maintaining the relative spacing of parallel spaced members, such as concrete forms, while at the same time providing support for such members.

Many devices, and combinations thereof, have been used in the past, particularly in the concrete construction industry, for maintaining the relative spacing of parallel spaced members, such as forms, and for supporting such members while in use. Such devices have been used with varying degrees of success as the art has evolved, but they have generally been found to be cumbersome and time consuming to use, and have not been readily adaptable to the uses for which they are intended.

Various problems, such as lengths of supports, means for attaching the supports to the forms, number of supports required, weight of supports, facility of use of such supports, and adaptability of supports to varying conditions of use presently confront the art. Such problems have persisted in the industry, and there has arisen a great need for a support which is easy to handle under conditions of use, and which is adaptable to varying requirements found where the supports are used.

It is an object of the present invention to provide a device for supporting and retaining parallel spaced members used in industries, such as the concrete construction industry, which is easy to use, and adaptable to varying conditions.

It is another object of the present invention to provide a device for supporting and maintaining parallel spaced members, such as concrete forms, which device is durable under extreme conditions, but which is not unduly cumbersome to use.

A further object of the present invention is to provide a device which may be used to support forms while at the same time retaining such forms in their positions relative to one another.

Another object of the present invention is to provide a device which is adaptable to supporting as well as retaining parallel spaced members, such as concrete forms, in place, and which is durable, relatively light in weight, readily attachable to such forms, and easily removed when its function is served.

Another object of the present invention is to provide a device for retaining the relative spacing of parallel spaced members, such as concrete forms, which can be re-used an indefinite number of times, is sturdy, but relatively light in weight, adaptable to use under varying conditions, easy to attach, and detach from such forms, and generally adaptable to use with any configuration of forms.

Other objects and advantages of the present invention will appear as the same is better understood from the following description.

The present invention includes the combination of a "whaler" with one or a plurality of "hairpins," which "whaler" and "hairpins" are used in combination with a "snaptie" for retaining the relative positioning of spaced members, such as concrete forms, and if the need arises for providing support for such forms.

As the skilled artisan knows, the terms "whaler," "hairpin," and "snaptie" are terms used in the construc-

2

tion industry, particularly where concrete construction is concerned, to designate various members adapted to retain, and sometimes to support, spaced members, such as concrete forms. A "snaptie," as used in the present invention, is an elongated pin having enlarged heads on either end. These pins are extended between forms, such as plywood slabs, and protrude through apertures provided in the forms at spaced intervals. The "whaler" serves the purpose of a support member and usually comprises one section of two-by-four lumber placed on the outside of each of the forms, along the longitudinal axis thereof, directly under the protruding ends of the "snapties," and another, usually smaller, piece of lumber placed directly over the protruding ends of the "snapties." These two pieces of lumber comprise the usual "whaler." The "hairpin" is usually a wedge shaped, elongated piece of material, such as cast iron, having a channel cut through it along its longitudinal axis, which channel opens into an enlarged aperture to receive the head the "snaptie." The "hairpin" is in position on the "snaptie" when it is placed across the gap between the two members of the "whaler," and the enlarged head of the "snaptie" is inserted into the enlarged aperture in the "hairpin" channel. The "hairpin" is then driven so that the outer shoulders of the channel come into contact with the head of the "snaptie" and since the channel is wedge shaped in cross section, the "snaptie" is urged outwardly from both sides of the forms, and is thus tightened as the wedge is driven between it and the "whaler."

As may be seen from the above description, the normal operation of securing forms in place is time consuming and cumbersome, requiring several men merely to attach the "hairpins" and "whalers." As will presently be seen from the ensuing description, much of the inefficiency of the operation is eliminated by the present invention.

A better understanding of the present invention can be obtained by reference to the drawings, wherein like numbers designate like parts, and accompanying detailed description contained herein.

Referring now to the drawings:

FIG. 1 shows the present invention in use on a set of forms;

FIG. 2 is similar to FIG. 1 except that the present invention is shown being used as a "strongback" as well as a "snaptie" clamp and form support;

FIG. 3 is a detailed showing of one of the "hairpin-whaler" combinations which form an important part of the present invention;

FIG. 4 is a cross-sectional view of the "hairpin-whaler" combination shown in FIG. 3;

FIG. 5 is an end view of the "hairpin-whaler" combination shown in FIG. 3;

FIG. 6 is a detailed showing of the present invention clamping a "snaptie" in an inside corner of a set of forms, and demonstrates a special use of the present invention;

FIG. 7 is a perspective showing of the double wedge "hairpin" used in the present invention;

FIG. 8 is a modification of the "hairpin-whaler" combination which forms a part of the present invention, showing a "whaler" of rectangular cross section.

Referring now to FIG. 1, there is shown therein "hairpin-whaler" combinations 20 comprising "whalers" 21, double wedge "hairpins" 22 and single wedge "hairpins" 23. Although FIG. 1 shows a combination of three "hairpins" per "whaler," it is to be noted that any number of "hairpins" can be connected to each "whaler," limited only to length of the "whaler," and the size of the "hairpins." The "whalers" 21 are shown generally in the drawings to be right angle members, such as angle iron, but

may consist of any members of suitable strength having a variety of cross sections, such as rectangular as shown in FIG. 8.

"Hairpin-whaler" combinations 20 are attached to forms 24, which are to be maintained in spaced relationship while retaining material such as concrete, by means of their co-action with "snapties" 25. Forms 24 are provided at spaced intervals with apertures 26, as shown in FIG. 6, through which "snapties" 25 project. "Snapties" 25 are of standard construction, and consist of a rod 27, an abutment cone 28 and a head 29. "Snapties" 25 are more specifically shown in FIGS. 4 and 6. The specific details of the "hairpin-whaler" combinations 20 and their co-action with "snapties" 25 and forms 24 will be described hereinafter.

Referring again to FIG. 1, it can be readily seen that the "hairpin-whaler" combinations 20 are adapted to be secured to the forms 24 in a manner to be hereinafter described, and may be so secured either in a vertical, horizontal or any other desired position limited only by the spacing of the "snapties." Further, it is obvious that "snapties" 25 extend between two spaced forms, and the co-action of the "snapties" with the forms and the "hairpin-whaler" combinations 20 provides support for forms 24 as well as maintaining their relative spacing.

"Hairpin-whaler" combinations 20 provide a connection between adjacent sections of forms 24, as shown in FIG. 1, and may be used to retain corners or other angles in forms both on the inside, as shown in FIG. 6, as well as the outside, as shown in FIG. 1. Referring now to FIG. 1, in order to facilitate retaining forms at an angular relationship with one another, "whalers" 21 are provided with apertures 30, and pins 31 are adapted to be inserted into two matched apertures at the junction of two forms 24 in the manner shown in FIG. 1. The insertion of pins 31 into matched apertures 30 in two "whalers" 21 forms a pivot so that any angle desired can be formed.

Referring now to FIG. 6, two forms forming the inside of an angle are retained in position by the abutment of their respective adjoining edges, and by single-wedge "hairpins" 23 co-acting with their respective "snapties" 25.

As shown in FIG. 1, either single-wedge "hairpins" 23 or double-wedge "hairpins" 22 may be attached to "whalers" 21. Whether the "hairpins" are single or double wedge will be determined by the use to which they are to be put. For example, double-wedge "hairpins" 21 have an advantage in that they may be driven from either of two directions, whereas single-wedge "hairpins" are advantageous in positions where space is limited, or it is possible to drive them in only one direction, such as an inside corner as shown in FIG. 6.

As is demonstrated in FIG. 1, the "hairpin-whaler" combinations 20 which are a part of the present invention have a great versatility in that they may be used to retain the spaced relation of forms 24, sides being useful as vertical or horizontal supports and to form corners or other angles in forms. Further, these "hairpin-whaler" combinations 20 are of a unitary construction, with the "hairpins" 22 and 23 being slideably attached to "whalers" 21 in a manner to be hereinafter more particularly described, so that each unit can be attached to a set of forms quickly, by a single individual, and detached with a minimum of effort.

The versatility of the present invention can be seen by reference to FIG. 2 wherein the "hairpin-whaler" combinations 20 are attached to forms 24 in such a manner as to provide a "strongback" support for such forms. When "hairpin-whaler" combinations 20 are to be used as "strongback" supports, support members are placed against forms 24, with "snapties" 25 extending through apertures therein, and "whalers" 21 are attached to "snapties" 25 and then clamped into place by "hairpins" 22 or 23 to hold both supports 32 and forms 24 in place. Such use of "strongback" supports is often necessary in cases where the forms 24 are raised to great heights, and where

75 a single support, placed either vertically or horizontally will not provide sufficient support to keep the forms from breaking apart or buckling when pressure is applied to them. Such an arrangement as that shown in FIG. 2 provides both vertical and horizontal support for forms, and is particularly desirable where several panels of forms are attached adjacent one another to obtain the desired height, for instance, of a concrete wall. As is shown in FIG. 2, support members 32 are usually of the same construction as "hairpin-whaler" combinations 20, so that these members can be used to secure "snapties," if desired, and eliminate the need for extending "snapties" 25 through the outside "hairpin-whaler" combinations at every point on the forms 24.

10 The specific details of each "hairpin-whaler" combinations 20 may be seen by reference to FIGS. 3-5. "Whalers" 21 consist of lengths of material, such as angle iron. Material of different cross section, such as rectangular, as shown in FIG. 8, circular or any other desired cross section, could be used for "whalers" 21. "Hairpins" 22 are attached to "whalers" 21 by pins 40, which pins extend through channels 41 in each "hairpin" 22. Heads 42 of pins 40 engage the shoulders 44 of channels 41 to secure each "hairpin" 22 to "whaler" 21. A double-wedge 22 is 15 shown in FIGS. 3-5 for simplicity in describing the attachment of each "hairpin" 22 to its respective "whaler" 21. It may be seen by reference to FIG. 6 that a single-wedge is attached to its "whaler" 21 in the same manner. As may be seen by reference to FIG. 3, channel 41 has an 20 enlargement 43 at its longitudinal center, or in the case of single-wedge "hairpins" 23 at their lower end, and "whaler" 21 is provided with an aperture or slot over which enlargement 43 may be positioned to receive one 25 end of a "snaptie" 25. Channels 41 are slightly smaller 30 in width than the diameter of "snaptie" heads 29. Cone 35 28 on "snaptie" 25 abuts the inside surface of a form 24, being retained on "snaptie" 25 by projection 45, and head 29 of "snaptie" 25 extends through the enlargement 43 of channel 41 and the aperture or slot in "whaler" 21. Head 29 then engages the shoulder 44 of channels 41 when "hairpin" 22 is moved in either direction. The 40 attachment of one double-wedge "hairpin" 22 to "whaler" 21 has been described for simplicity, but it is obvious that a multiplicity of "hairpins," either double or single wedge, could be attached to a "whaler" 21 if desired, limited only by the length of the "whaler" and size of the "hairpins." The specific construction of a double-wedge "hairpin" 22 can be better seen by reference to FIG. 7.

45 The operation of the present invention is as follows: Forms 24 are erected with both ends of the desired number of "snapties" 25 projecting through apertures in a set of forms 24, as is the normal course of business. "Snapties" 25 extend between two opposite spaced forms 24. Each end of a "snaptie" 25 projects through an aperture 50 in one of the pair of forms. "Whalers" 21 and their attached "hairpins" 22 and 23 are then positioned with their respective "snaptie" receiving apertures or slots over the projecting heads 29 of "snapties" 25, and heads 29 of "snapties" 25 project into enlargement 43 of their respective 55 "hairpins" 22 to therein engage shoulders 44 of channels 41. Pressure, for instance by hammering, is applied to drive shoulders 44 of channels 41 into closer engagement with the heads 29 of "snaptie" 25 forcing "hairpin-whaler" combinations 20 into close engagement with one 60 side of forms 24, and cone 28 of "snaptie" 25 into close engagement with the other side of form 24, thus tightly attaching each "hairpin-whaler" combination 20 to form 24. It is obvious that "snapties" 25 have a first and a second end. When the second end of the "snaptie" 25 is 65 attached to a form 24 opposite and spaced from that to which the first end of "snaptie" 25 is attached, the two members are retained in their relative positions and are supported. As is shown in FIG. 1, "hairpin-whaler" combinations 20 may be attached either in a vertical position, 70 or a horizontal position, on forms 24 depending on the 75

need of the user. The unified "whaler" members 21 to which are attached a plurality of "hairpins" 22 and 23 provide support for forms 24 and co-act with "snaptie" 25 and "hairpins" 22 and 23 to maintain the relative spacing between a pair of spaced forms 24. As is also shown in FIG. 1, "hairpin-whaler" combinations 20 may be used to support corners in forms 24 by aligning apertures 30 of intersecting "whalers," and placing pin 31 through the two aligned apertures 30 to form a pivot.

As is shown in FIG. 2, the chief difference in the operation of the present invention when used as a "strongback" is that some of "snapties" 25 must project through apertures in support members 32 prior to being attached to "hairpin-whaler" combinations 20. The attachment of the "hairpin-whaler" combination 20 to "snapties" 25 is then accomplished as was described previously with reference to FIG. 1.

It should be noted that in normal uses, "snapties" 25 are spaced along forms equal distance from each other, such as sixteen inches apart, so that "hairpin-whaler" combinations 20 can be designed to match this standard spacing. "Whalers" 21 are placed over "snapties" 25, and "hairpins" 22 or 23 are positioned over "snaptie" heads 29 and driven into tight engagement to complete the operation. When removal of the "hairpin-whaler" combinations 20 is desired, "hairpins" 22 and 23 are loosened, and "hairpin-whaler" combinations 20 are simply lifted away from forms 24.

In uses where a "hairpin" 22 can be moved in only one direction, such as in an inside corner as shown in FIG. 6, a single-wedge "hairpin" 22 can be used. In normal uses, a corner or other angle is formed on the outside as has been previously described with reference to FIG. 1. The inside of the corner or other angle is formed in the following manner, with reference to FIG. 6. Two forms 24 are placed in abutment at the proper angle, such as a right angle, the ends of "snapties" 25 project through apertures in forms 24, and single-wedge "hairpins" 23 are positioned over heads 29 of "snapties" 25 in the same manner as was previously described with reference to the double-wedge "hairpins" 22. "Hairpins" 23 are then driven into engagement with heads 29 of "snapties" 25. Forms 24 are thereby held in their desired position by the "snapties" 25 and their co-action with "hairpin-whaler" combinations 20.

As may be seen from the above description, the present invention provides a supporting and clamping device for parallel spaced members, such as concrete forms which is sturdy, durable, relatively light in weight and easily attached and detached from the members it supports.

Obviously many modifications and variations of the present invention are possible in the light of the above teachings. It is, therefore, to be understood that within the scope of the appended claim the invention may be practiced otherwise than as specifically described.

What is claimed is:

In a clamping device for spaced form members having apertures therethrough, the form members being spaced so as to have facing surfaces and so as to have the apertures in one form member substantially in alignment with

a corresponding aperture in the opposite form member, the combination comprising "snaptie" means extending between said spaced form members; "whaler" means; and "hairpin" means; said "snaptie" means comprising a plurality of elongated rod-like members having first and second ends, which ends are enlarged relative to the diameters of the rod-like members, and two abutment members fixedly attached to each of said rod-like members and spaced from said first and second ends respectively, said enlarged ends of each rod-like member extending through aligned apertures in the spaced form members, and said abutment members abutting against the inner faces of the forms to space said forms apart; said "whaler" means comprising an elongated metal member having a plurality of slots spaced therealong and extending from an edge of the elongated member inwardly toward the longitudinal axis of the elongated member, said elongated member being positioned so as to have each slot receive one of the ends of said "snaptie" means which ends extend through the apertures in said spaced form members; said "hairpin" means comprising a plurality of wedge-shaped elongated members each having a channel therein along the longitudinal axis thereof, which channel is generally of less width than the diameter of the enlarged ends of said "snaptie" means and is enlarged in one portion for receiving an enlarged end of said "snaptie" means; attachment means fixedly attached to said "whaler" means and engaging said "hairpin" means whereby said "hairpin" means are slidably attached to said "whaler" means and form a unit therewith, and the channels in said "hairpin" means intersect the slots in said "whaler" means and each receive an enlarged end of one of said "snaptie" means so that said "whaler" means and said "hairpin" means engage said "snaptie" means as a unit, and said "snaptie" means, said "whaler" means and said "hairpin" means coact to retain the forms in position; said attachment means comprising at least two pins each having one end attached to said "whaler" means and another end enlarged, whereby the enlarged ends engage the outer portion of the channel in said "hairpin" means to slidably attach said "hairpin" means to said "whaler" means and position the channels to pass over and intersect the slots in said "whaler" means.
